UNITED STATES PATENT OFFICE.

HENRY PICKFORD AND HARRY T. GREGORY, OF CHELSEA, MASS.

ELECTRIC SIGNALING APPARATUS.

SPECIFICATION forming part of Letters Patent No. 252,797, dated January 24, 1882.

Application filed July 27, 1881. (Model.)

To all whom it may concern:

Be it known that we, HENRY PICKFORD and HARRY T. GREGORY, of Chelsea, in the State of Massachusetts, have invented an Improvement in Electric Signaling Apparatus, of which the following is a specification.

This invention relates to the devices by which the electric current in telephonic and other sound or signal transmitting apparatus is cut out or shunted, in order that such current may traverse the conducting-coil or pass through the shorter path, as may be desired; and the invention will, in connection with the accompanying drawings, be hereinafter fully described, and specifically defined in the appended claims.

Figure 1 is a front elevation of an instrument having our improvement applied thereto, and shown in the inclosing-case, from which the cover is removed, as secured to the wall or vertical support. Fig. 2 is a horizontal section taken on line *x*, Fig. 1. Fig. 3 is a detached section taken through the axis of the crank-sleeve, its threaded socket, the elastic contact-finger, and its securing-screw. Fig. 4 is a detached view, showing the side of the case in vertical section, and the contact-washer, a portion of the crank-shaft, the crank, and the contact-finger in elevation. Fig. 5 is a detached vertical section taken on line B B, Fig. 1.

In said views, A represents the wall or vertical support, to which the back *a* of the case is secured, and to said back the horseshoe-magnets *b b* are secured in the usual manner, and are inclosed by the walls of the case, the sides of which are shown at *c c* and the ends at *d d*. At the open end of said magnets *b* is journaled the small arbor *f*, upon which are mounted the armatures and insulated conducting wire or coils, as shown in elevation at *e* in Fig. 2; and upon said arbor *f* is mounted the friction-disk *g*, which is engaged by the grooved faced driving-disk *h*, which is rigidly mounted upon arbor *i*, which, when rotated, carries its said disk *h*, and the frictional contact thereof with disk *g* serves to rotate its arbor *f* and the said armatures and coils of wire thereon mounted; but as all the parts thus far referred to are old and well known, and may be of any of the usual kinds, a further or more detailed description is not deemed necessary.

For the purpose of journaling and supporting said shaft *i*, we have invented the following means or devices: Upon the disk *m*, in which one end of arbor *f* is journaled, we form the 55 socketed arm *l*, in which is closely fitted the round arm *k*, formed upon sleeve *j*, in which latter said arbor *i* is mounted and revolves. The arm *k*, being round and secured in position by set-screws *n*, Fig. 4, admits of the desired delicate adjustment, both lineally and in plane, of disk *h* relatively to disk *g*, in order to secure the desired amount of frictional contact between them, said arbor *i* being held from lineal displacement relatively to its sleeve *j* 65 by means of the engagement of disk *h* with said disk *g*, the arbor *f*, upon which the latter is mounted, being shouldered in its bearings, and so held from end motion.

For the purpose of making and breaking contact in order to cut out or change the direction of the current, we have invented the following devices: A socket, *n*, having a round angle-arm, *t*, is threaded or otherwise removably attached to shaft *i*, outside of the case. Upon 70 said angle-arm *t* is mounted a coiled spring, *v*, and a crank-arm, *y*, the latter having an axial passage equal to the outer diameter of spring *v*, to receive both said spring and the arm *t*, which latter is inserted in said spring. The 75 ends of said spring *v* are respectively secured in the wall of socket *n* and in the body of arm *y* at the base of its axial passage, as shown in Figs. 2, 3, in order that the torsional force of such spring may actuate arm *y*, in the manner 80 and for the purpose to be described. A short arm, *a'*, which is an extension of the wall of arm *y*, extends across and beyond the diametric face of socket *n*, the inner face of said arm *a'* being arranged at a sufficient distance from the 85 diametric face of the socket to allow a slight rocking or rotary motion of arm *y* on the interior arm, *t*. A screw, *b'*, is threaded in arm *a'*, exactly opposite arm *t* of socket *n*, and at such distance from said socket that the elastic coiled 90 wire finger *c'*, which is secured on said screw, by its threads engaging the coils of the spring, will, by its contact with socket *n*, prevent lineal displacement of arm *y*. Said screw *b'* is so positioned in arm *a'* and the elastic finger *c'* is of 95 such length that when at rest said finger will bear against the insulated and perforated disk 100

d', secured to side *c* of the case, and through which shaft *i* passes, as shown by solid lines in Fig. 1; but when force is applied to the handle or wrist-pin *z* of crank-arm *y* in the direction indicated by an arrow in Figs. 1, 4 (for the purpose of rotating shaft *i* and its disk *h*) the crank arm *y* will be slightly rocked upon the interior arm, *t*, thereby vibrating finger *c'* and disconnecting it from disk *d'*, as is shown by dotted lines in Fig. 1 and by solid lines in Figs. 2, 4; but when handle *z* is released the torsional force of spring *v*, acting upon arm *y*, will rotate or rock the same so as to bring finger *c'* again into contact with disk *d'*.

15 The practical employment or operation of our invention is as follows: The usual line-wire "in" is shown and indicated in Fig. 1, and is so connected that the current entering thereby will, when not shunted, pass through 20 the coils *e'* on arbor *f*, and thence through the "out" line, (shown in Fig. 2;) but when the crank is at rest the current will pass in the usual manner through arbor *i*, its crank, finger *c'*, disk *d'*, and the "shunt" line, (shown 25 and indicated in Fig. 2,) and thence by the indicated main out line; but when it is desired to cut out the shunt in order to send the current through coils *e'*, in order to sound a call-bell in the main office, or for other purposes, 30 the disk-shaft *i* is rotated by the means described, and the force exerted for that purpose on the crank-handle *z* will, as explained, disconnect finger *c'* from disk *d'*, thereby insulating the same, when the current must pass 35 through the said coils, as before stated; and hence this part of our invention has relation to the devices by which the current may be cut out, so as to compel it to either pass through said coils or to avoid the same, as may be desired.

We do not claim in the abstract a generator having its circuit automatically broken by the revolution of the driving mechanism; but

We do claim as follows:

1. In an electrical instrument, the combination of the support *m* of arbor *f*, formed with the socketed extension *l*, and the sleeve-like bearing *j* of arbor *i*, formed with the cylindrical extension *k*, to be seated, adjusted, and 50 locked in socket *l*, whereby the driving-disk *h* on arbor *i* can be adjusted both linearly and in plane relatively to disk *g* on arbor *f*, substantially as specified.

2. In an electrical instrument, the combination of hollow crank-arm *y*, with its handle *z*, the internal arm, *t*, the coiled spring *v*, the short arm *a'*, and a contact-finger projecting therefrom, all substantially as specified.

3. In an electrical instrument, and in combination with its electric circuits, a crank-arm constructed and arranged to be rocked, rotated, or vibrated by the force exerted upon its wrist-pin or handle, and a contact-finger projecting from such crank-arm and arranged to be thereby vibrated to make and break contact, substantially as specified.

4. In an electrical instrument, and in combination with its electric circuits, an actuating-crank constructed and arranged to rock, rotate, or vibrate, and an elastic yielding contact-finger arranged to make and break contact by the action of such crank, substantially as specified.

5. In an electrical instrument, a contact finger or point composed of the securing-screw *b'*, suitably secured and supported, and the coiled wire spring *c'*, mounted upon and held in position by the engagement of its coils with the threads of said screw, substantially as 75 specified.

HENRY PICKFORD.
HARRY T. GREGORY.
